Filed Sept. 16, 1965, Ser. No. 487,842
5 Claims. (Cl. 248—346.1)

ABSTRACT OF THE DISCLOSURE

A coaster having a base of an absorbent material and a plurality of spaced-apart lines of a non-absorbent material attached to the top surface of the base. The lines extend to a height above the base to cause the droplets to be sucked into the base, and they are printed onto the base.

This invention relates to a coaster and a method of making same.

The subject matter of this invention is a coaster of the type used under a tumbler or other container which tends to collect condensate which ultimately drains off the tumbler and onto any support below the tumbler. It is of course common practice to place a coaster under the tumbler so that the drainage will not get onto the table top or like support. These heretofore known coasters are sometimes made of water-proof plastic, metal, and like water-proof material. They are also sometimes made of an absorbent material made of paper stock or the like which sucks or blots up the drainage from the tumbler.

The rigid type of coaster, such as that made of metal or plastic, is generally expensive and not a disposable type and is therefore not to be preferred in the requirements of this present invention. Also, the paper or blotter type of coaster heretofore known has been found to be ineffective in keeping the condensate from the table top, and it has also been found that the coaster has a tendency to adhere to the bottom of the tumbler when a certain amount of condensate is disposed between the tumbler and the coaster. Then when one picks up the tumbler, the coaster adheres or sticks to the bottom of the tumbler, and this is contrary to the desired function of the coaster to have it remain on the table top when the glass or tumbler is picked up.

It is a general object of this invention to provide a coaster and a method of making same wherein the coaster is an improvement over those heretofore known in that it is more reliable and efficient in its action of protecting the table top and avoiding the dripping of the condensate or spillage from the tumbler onto the drinker.

Another general object of this invention is to provide a coaster and method of making same wherein the coaster may be readily and inexpensively provided in that for instance it can be made from a paper stock and can be run through a printing process and can be finally cut into the individual sizes, all being performed on one large sheet so that the coasters can be rapidly and mass produced.

Still another object of this invention is to provide a coaster and method of making same wherein the coaster will not adhere to the bottom of the tumbler when the tumbler is raised, and wherein the coaster is effective in inducing the condensate to drain off the tumbler and be absorbed by the coaster.

Still another object of this invention is to provide a coaster and method of making same wherein the coaster will have a long life in that it can absorb a considerable quantity of condensate and remain effective in keeping the condensate from forming on the tumbler to a degree where it will drain onto the drinker when the tumbler is raised.

2

Other objects and advantages will become apparent upon reading the following description in light of the accompanying drawings, wherein:

FIG. 1 is a top plan view of a preferred coaster of this invention.

FIG. 2 is a side elevational view of the coaster of FIG. 1 but showing the tumbler in full lines whereas FIG. 1 shows the tumbler in dot-dash lines.

FIG. 3 is an enlarged view of the lower right hand corner of FIG. 2, with a part thereof broken away and with a showing of two droplets of condensate.

FIG. 4 is an enlarged sectional view taken on the line 4—4 of FIG. 1.

The coaster is shown to consist of a base 10 which is a flat sheet having a flat top surface 11. The base 10 is made of a blotter-type of material which readily absorbs water, and it has been found that a material which will absorb one cubic centimeter of water in one minute is suitable for this coaster. This capacity for absorbing is also found to be of a characteristic which will cause moisture to rise one inch on a strip of the base 10 when it is immersed one-eighth inch and the one inch rise will be in one minute. The material having these characteristics is thus a blotter-type material or a moisture absorbing material, and it may be further stated that it has been found that the material will absorb one cc. of moisture in a continuous and rapid manner as one watches the absorption with a naked eye.

The base 10 is thus shown to be of a sheet material of blotter stock which is a paper stock material. It has a water-proof sheet 12 affixed to the lower surface of the base 10, and the sheet 12 would of course protect a table top or the like from receiving any moisture which is sucked in or absorbed by the base 10. It will of course also be apparent that the water-proof sheet 12 may be eliminated and the base 10 can be placed in a water-proof tray of any suitable material so that the table top will not become wet.

An important feature of the invention is the provision of the lines 13 and 14 which are superimposed on the base 10 and extend a slight distance above the top flat surface 11, as shown. The lines 13 and 14 may be provided by printing process, and they may be of an ink material which of course will not be absorbed by the base 10 since the material used to form the lines 13 and 14 is of a viscosity which prevents its absorption into the base 10. Thus the lines 13 and 14 can be applied to the base 10 to be applied in a liquid form but yet end up in a raised position with respect to the top surface 11, as shown.

Where the line 13 and 14 are applied by a printing process, they may be engraved or it may be raised printing or of course it may also be a silk screening process. As shown, the lines 13 are heavier than the lines 14, but both lines extend above the level of the top surface 11. Thus the tumbler 16 would normally be disposed on the lines 13 so that the tumbler would be spaced above the top surface 11 from the tumbler's lower base or surface 17. FIG. 1 shows the tumbler 16 in dot-dash lines, and it also shows a ring 18 which is concentric with the radical lines 13 and 14 to serve as a decorative design and a guide for placing the tumbler 16 directly on the lines 13 and 14.

As mentioned, the lines 13 and 14 are made of a non-absorbent material, and thus any condensate formed on the tumbler 16 will flow over the lines 13 and 14 and be sucked off or attracted into the absorbent material forming the base 10. Since the tumbler 16 is spaced above the base 10, when one picks up the tumbler 16 the condensate does not form an adhering force which will cause the coaster to be picked up with the tumbler 16. This is an important feature of the invention.

FIGS. 3 and 4 show the formation of condensate droplets, designated 19 and 21 in FIG. 3 and 22 in FIG. 4. Of course the droplet 19 would drain down to the position of the droplet 21, in FIG. 3, and the droplet would flow further downwardly around the line 13 and would hang from the tumbler to a point where it would touch the top surface 11 and thereby be sucked or attracted by the base 10 to be absorbed thereby, as indicated in FIG. 3. Of course once the condensate is absorbed in the base 10 it cannot touch the bottom of the tumbler and thus will not be able to drip onto the drinker, and also the tumbler will not pick up the coaster. FIG. 4 shows this with the droplet 22, that is, the droplet will cling to the tumbler 16 and hang therefrom (all in a usual manner of condensate formation and drainage) and the droplet will contact the absorbent material 10 to be attracted thereto, and thus absorbed by the material or base 10.

Thus it is significant that the lines 13 are spaced and extend above the top surface 11 in their maximum spacing or top 23 to an amount less than the amount which the condensate droplet 22 hangs below the tumbler 16. That is, the droplet 22 will hang from the tumbler 16 but will also touch the base 10, and the lines 13 permit this. It has then been found that the height of the lines 13 above the top surface 11 is preferably from 50 to 250 microns in order to perform the desired function. The height of the lines 14 above the surface 11 can be at the lower end of the range just mentioned, and these lines are available for supporting the tumbler and reinforcing the lines 13 in the event the latter become shorter or pressed into the material 10. However, it has been found that the lines 13 alone would be sufficient.

The lines 13 and 14, if the latter are to be applied, may be applied by the printing processes mentioned and others that are known, or they may also be lines of plastic or any other material which is non-absorbent and suitable for the characteristic and purpose mentioned.

The method of making the coaster is therefore one where the blotter material 10 has the lines 13 applied thereto, by printing or other processes depending upon the desired process and the material used in the lines 13, and the sheet 12 may also be then applied to a large sheet forming the base 10. This large sheet may then be cut into the smaller sheets for individual coasters as shown in these drawings. In this manner, a method of providing a coaster which is efficient in absorbing the moisture and which will preclude the coaster from sticking to the tumbler when the tumbler is raised, is provided herein.

It is also to be noted that the thickness of the base 10 is several times the height of the lines 13 above the top surface 11. FIG. 4 shows that the relationship is approximately five to one. Also, the base 10 is of a card stock, that is, it is a rigid material which is stiff and supports its own weight.

While a specific embodiment of this invention has been shown and described, it should be obvious that certain changes could be made therein and the invention should therefore be determined only by the scope of the appended claims.

What is claimed is:

1. A coaster for absorbing the droplets of condensate draining from a tumbler, comprising a base of an absorbent material having an affinity for water and being capable of rapidly absorbing water into the body of said material when the water comes into contact with the surface of said material, said base having a flat top surface, and a plurality of spaced-apart lines of a non-absorbent material printed into said base and permanently attached thereto and superimposed on said flat top surface of said base and extending a slight distance thereabove for supporting the tumbler in a position spaced above said

base and being disposed on said base in an arrangement to have the condensate droplets come into contact with said top surface while those droplets are still clinging to the tumbler so that those droplets are sucked from the tumbler and into said base by the affinity of said absorbent material.

2. A coaster for absorbing the droplets of condensate draining from a tumbler, comprising a base of an absorbent material having an affinity for water and being capable of rapidly absorbing water into the body of said material when the water comes into contact with the surface of said material, said base having a flat top surface, a plurality of spaced-apart lines of a non-absorbent material attached onto said flat top surface of said base, and with each of said lines extending a slight distance above said top surface for supporting the tumbler in a position spaced above said base and being disposed on said base in an arrangement to have the condensate droplets come into contact with said top surface while those droplets are still clinging to the tumbler so that those droplets are sucked from the tumbler and into said base by virtue of the affinity of said absorbent material, and a water-proof material attached to said base and on the side thereof opposite said non-absorbent material for supporting said base on a table top or the like.

3. A coaster for a tumbler, comprising a base of a water-absorbent blotter material capable of absorbing water at a rate of one cc. in one minute, and spaced-apart lines of non-absorbent material printed into said base to be superimposed on said base and extend to a height a slight distance thereabove to have condensate attracted off the tumbler and sucked into said base by the absorbency of said absorbent material and to support said tumbler spaced above said base, the height of said non-absorbent material above said base being less than the overhang of condensate droplets below the tumbler so that those droplets contact said base to be blotted into said base.

4. A method of making a coaster for sucking droplets of condensate draining off a tumbler, comprising the steps of forming a sheet of blotter material with a flat surface, printing on said flat surface with spaced-apart lines of non-absorbing ink having a viscosity which permits the ink to lay on top of said sheet rather than be absorbed by said sheet and arranging the ink lines to be slightly raised on said flat surface a slight distance which is less than the distance the droplets hang down from the tumbler, and cutting said sheet into parts which individually form a coaster.

5. A method of making a coaster for sucking droplets of condensate draining off a tumbler, comprising the steps of forming a sheet of blotter material with a flat surface and capable of absorbing water at a rate of one cc. in one minute, printing on said flat surface with spaced-apart lines of non-absorbing ink having a viscosity which permits the ink to lay on top of said sheet rather than be absorbed by said sheet and arranging the ink lines to be slightly raised on said flat surface a slight distance which is 50 to 250 microns, adhering a water-proof sheet to the first-mentioned sheet on the face opposite said printing, and cutting said sheets into parts which individually form a coaster.
